Harry J. Roberts, University Heights, Ohio, as-
signor to Roberts Designs, Inc., Cleveland, Ohio

Application May 27, 1947, Serial No. 139,296

Term of patent 14 years

(Cl. D80—2)

To all whom it may concern:

Be it known that I, Harry J. Roberts, a citizen of the United States, residing in the city of University Heights, county of Cuyahoga, and State of Ohio, have invented a new, original, and ornamental Design for an Automobile Lubrication Display Fixture, of which the following is a specification, reference being had to the accompanying drawing, forming a part thereof.

Figure 1 is a perspective view of an automobile lubrication display fixture showing my new design; and

Figure 2 is a perspective view of individual parts in unassembled relation, the broken lines being shown for illustrative purposes only.

I claim:

The ornamental design for an automobile lubrication display fixture, substantially as shown.

HARRY J. ROBERTS.
